UNITED STATES PATENT OFFICE.

MAX A. SKALL, OF NEW YORK, N. Y.

COLLAPSIBLE LANTERN.

1,318,614.

Specification of Letters Patent. Patented Oct. 14, 1919.

Application filed September 10, 1918. Serial No. 253,375.

To all whom it may concern:

Be it known that I, MAX A. SKALL, a citizen of the United States, and residing at New York city, in the county and State of New York, have invented certain new and useful Improvements in Collapsible Lanterns, of which the following is a specification.

This invention relates to collapsible lanterns and more particularly to that class of such lanterns which are intended for the use in the field and in camps. It is the object of this invention to provide an improved device of this character comprising a minimum of parts, secured together to prevent their loss and to be conveniently and simply arranged to be instantly collapsed or extended and adapted for use in standing or suspended position. Another important feature of this collapsible lantern is its adaptation for use as a heater for small quantities of water, food, etc.

With these and similar objects in view the invention consists in certain novel details of construction and arrangements of parts hereinafter described and shown and illustrated in the accompanying drawings, made part of the specification in which:

Figure I is a front elevation of the lantern in expanded position.

Fig. II is a side elevation of the same.

Fig. III is a plan view of Fig. II.

Fig. IV is a plan of the lantern in collapsed condition.

Fig. V is a part of a sectional side elevation on the line A—A of Fig. VI.

Fig. VI is a sectional side elevation on the line B—B of Fig. V.

Fig. VII is a plan, partly in section on the line C—C of Fig. I. The handle and hood are turned sidewise in this figure to illustrate their position for cooking purposes.

Fig. VIII is a front elevation of the lamp in collapsed condition, some parts are broken away to more clearly show the interior arrangement.

Fig. IX is a sectional detail of the adjustable candle holder.

Similar characters of reference indicate corresponding parts throughout the various views.

My collapsible lantern is formed by the framed panels 1—2—3—4—5—6—7—8, which are hinged together horizontally by means of hinges 9 which are preferably riv-

eted to the U shaped channels forming the frames of the panels. The upper horizontal edges of panels 1—3—5—7 are hinged to the upturned edges of top plate 10 by means of hinges 10^a and the lower edges of panels 2—4—6—8 are hinged to the downwardly turned edges of bottom plate 11 by means of hinges 11^a. A preferable method of fastening these panels to the hinges is to extend and bend the hinge rods 10^b and 11^b—in such a manner that they penetrate through corresponding openings in the channel frames, and rivet them, forming a head on the outside faces of the panels, as shown in Figs. V to VIII. Panels 1 and 5 carry latch rods 12 rotatably fastened to their lower channel frames and bent at the corners of the lantern casing to form latches 12^a which engage corresponding pins 13 fastened to panels 3 and 7. These latches lock the lantern in expanded position and prevent an outward bulging of the panels. It will be noticed (see Fig. VII) that the panels 3—4 and 7—8 are longer horizontally than panels 1—2 and 5—6 so that the edges of the latter panels fit in the spaces between the inner faces of panels 3—7 and 4—8 respectively. The bottom plate 11 is of square shape, its four edges are bent vertically downward and form hinges for the lower panels, the plate is suitably provided with a number of air inlet openings 11^c and four spherical feet 11^d adapted to raise the downwardly turned edges of the plate 11 sufficiently above a supporting surface for air inlet purposes. The center part of plate 11 is provided with a circular depression adapted to support a candle. Candle holding jaws 14, suitably bent from sheet material and provided with a slot 14^a, are slidably held on bottom 11 by means of screws 14^b fastened to said bottom, and held in a place, suitable to the diameter of the candle, by means of nuts 14^c (see Fig. IX). The top plate 10 is like bottom plate 11 of square shape, but its four edges are bent vertically upward and form the hinges 10^a for the upper panels. In the center of the plate a square opening 10^c is made by cutting two diagonal slots and rolling the material so freed, into four tubes 10^d of such diameter that their highest points protrude above the upturned edges of plate 10. A pair of bent arms 15 provided with eyes 15^a at their upper ends, approximately above panels 1 and 3, are hinged to plate 10 along one of

its horizontal axes by means of hinges 15^b; to the eyes 15^a a bail or handle bar 16 is linked, by means of eyes 16^a. On each of the longitudinal bars of the handle slides an eye 17^a, bent at the ends of a horizontal hinge rod 17 to which the two blades of the hood or roof 18 are hinged. In normal, extended position the lower edges of the roof blades engage the inside of the upturned edges of plate 10 below and along the hinges 10^a for panels 1 and 5; the ends 18^a of wings 18 are bent downward parallel to panels 3 and 7 to prevent excessive draft through the hood and are notched at 18^b to rest 15 securely in central position on panels 1 and 5 in collapsed position (see Fig. VIII). The operation of this collapsible lantern is extremely simple, to expand the lantern from its collapsed condition shown in Fig. 20 VIII it is only necessary to lift the lamp by means of the bail or handle bar 16, whereby the eight panels aline themselves to vertical position by gravity. The lock bars 12 will then be turned that the latches 12^a engage 25 pins 13 which prevents the outward bulging of the panels, although the panels have no tendency to bulge outward under vertical pressure as soon as they are brought to vertical alinement, as the panels form toggle joints in balanced condition and no vertical force or horizontal pressure can disturb this condition. The hood is then adjusted by shifting eyes 17^a upward on bars 16 and dropping wings 18 down again 30 within the confining edges of plate 10. It will be noticed that by lifting handle 16 the swinging eyes 15^a and rods 15 automatically aline themselves with handle bars 16 and that the bail 16 has no tendency to 35 fall over on its side where erected, as it is held in vertical alinement by eyes 17^a which prevent its swinging about eyes 15^a. Should it be desired to place a cooking utensil upon the lamp, for instance to heat a quantity of water for shaving in camp, such utensil rests on the four tubes 10^a and the hood is swung into vertical position by 40 means of handle bar 16 as shown in Fig. VII. To collapse the lamp the above process is reversed, the handle bars 12^a are 45 turned to free the panels and a slight pull on these handles collapses the lamp. The hood is adjusted to the position shown in Fig. VIII by sliding eyes 17^a on bars 16 and opening its wings on their common 50 hinge, the swinging of eyes 15 permits the depositing of the hood in desired central position. The adjustable candle holder permits by means of its sliding jaws, the use 55 of candles of different diameters and assures their secure clamping. The opening 11^a in the depression of plate 11 avoids an accumulation of drippings from the candle. It 60 will be noticed that in collapsed condition 65 the vertical blades 14 of this candle holder

protrude through opening 10^c in the top plate; if the hood is shifted to one side (similar to its position shown in Fig. VII) while the lantern is collapsed, the candle holder is freed for insertion of the candle 70 and the lantern may serve as an ordinary candle holder for a free candle.

While from the foregoing description the advantages of this collapsible lantern are apparent, it may be stated that its principal 75 advantage is the extremely short time required for its expansion and collapsing and its compact arrangement, as the lantern has no separable parts which can be misplaced or lost.

Having thus described my invention, what I claim as new and desire to secure by Letters Patent is:

1. In a lantern, a casing consisting of a bottom plate, a top plate, and vertical side 85 plates, each side of said casing being formed by a pair of framed panels, hinges connecting the upper panel of each pair to said top plate and the lower panel of each pair to said bottom plate, hinges connecting the panels 90 of each pair horizontally at their joining edges, to permit collapsing of said casing and a latch on said casing, consisting of a 95 rotatively mounted rod, having ends adapted to join simultaneously two parallel panels on opposite sides of said casing to prevent its collapse under vertical pressure.

2. In a device of the kind described, a casing, consisting of a top plate, a bottom plate, and a plurality of panels, hinged to each other in pairs, each pair being hinged to the top plate and to the bottom plate of said casing, and independent locking means, movably attached to one of said panels, forming a coöperative couple to simultaneously 100 join parallel panels on opposite sides of said casing.

3. In a device of the kind described, a casing, a cover plate thereon, a movable arm rotatably held on said cover plate, a bail or 110 handle linked to said arm and a hood slidably mounted on said bail.

4. In a device of the kind described a casing, a cover plate thereon, a pair of wings, adapted to form a peaked hood above said 115 cover plate, and a pail providing means to remove said wings from their position above said cover plate, to a position outside of the side walls of said casing.

5. In a device of the kind described, a casing, a cover plate thereon, having its edges extending upwardly therefrom, an oscillating handle attached to said cover plate, a hood slidably mounted on said handle, said hood being adapted to be confined laterally 125 by the edges of said cover plate, forming means to hold said handle in vertical alinement.

6. In a device of the kind described a casing, consisting of a cover plate provided with 130

flanges, extending upwardly therefrom along its edges, a bottom plate provided with flanges extending downwardly therefrom along its edges, side plates consisting of a 5 pair of framed panels, hinged together at their horizontal joining line, leaning against the outsides of said flanges and hinges on said flanges to permit simultaneous outward movement of said side plates.

10 7. In a device of the kind described, a casing, a cover plate thereon, flanges extending upwardly from each edge of said cover plate, hinges on said flanges, to hold the side plates of said casing, a central aperture 15 in said cover plate and distance pieces extending from said top plate in upward direction beyond the edges of said flanges adapted to form a support for a cooking utensil.

20 8. In a device of the kind described a col-

lapsible casing, an oscillatable bail or handle held on said casing, and a pair of wings hinged to each other and adapted to form a hood, and slidably connected to said bail.

9. In a device of the kind described a casing, a top plate thereon, a bail rotatively attached to said casing, a pair of hinged wings supported by said bail to swing freely above said top plate and means to hold said wings in position above said casing to form a 25 30 peaked hood.

10. In a device of the kind described a casing comprising a top plate, a bottom plate, side plates adapted to fold outwardly about axes midway between said top and bottom plates and locking means held on one of said side plates, adapted to embrace the adjacent side plate when in extended position, to prevent bulging in outward direction. 35

MAX A. SKALL.
